York, N. Y., a corporation of New York

Application July 16, 1935, Serial No. 31,634
In Great Britain July 17, 1934

9 Claims. (Cl. 164—60)

This invention relates to improvements in web cutting mechanism of the kind comprising a plurality of spaced discs which co-operate with cutting abutments to cut a web into ribbons of a width equal to the separation between adjacent discs.

According to the present invention the plurality of discs are movable as a unit to effect a side-lay adjustment and each disc is individually movable to effect adjustment between adjacent discs and, moreover, the cutting abutments are correspondingly adjustable.

The invention is illustrated in the accompanying drawings in which Figure 1 is a side elevation 15 partly in section, and Figure 2 an end elevation.

In the drawings 1 indicates a web which is passed around rollers 2, 3 to the mechanism according to this invention, this mechanism operating to slit the web into ribbons which are 20 variously directed as desired, two leads of the ribbons being indicated at 4, 5, these leads passing from a common roller 6 to deflecting rollers 7, 8.

The slitting mechanism, which is located between the rollers 3, 6, comprises a first shaft 9 carrying hubs 10 to which slitting discs 11 are secured. The hubs 10 are a sliding fit on the shaft 9 so that they can be individually adjusted on the shaft and each hub is provided with a 25 grub screw 12 whereby the hubs and their discs can be secured to the selected position on the shaft 9. This shaft is carried at its ends and at points between the ends in bearings on arms 13 which are secured to a second shaft 14 parallel 30 with the first shaft 9. One end of the second shaft 14 is rotatably mounted in, but prevented from axial movement with respect to, a sleeve 15 which is mounted to slide in a part 16 of the machine frame and is formed with an arm 17 engaged between shoulders 18, 19 on a screw 35 threaded member 20, screwed into the part 16, this member 20 being provided with an operating hand-wheel 21. The other end of the second shaft 14 is slideable in, but prevented from rotary 40 movement with respect to, a second sleeve 22 which is rotatably mounted in a second part 23 of the machine frame and this second sleeve 22 is provided with an operating handle 24 by means of which the sleeve and hence the second shaft 45 can be rocked, a locking bolt 25, passing through an arcuate slot 26 in the handle 24, being provided for locking the arm against movement.

It will now be seen that when the hand-wheel 21 on the screw-threaded member 20 is rotated, 50 this member causes the first sleeve 15 to slide in

the support 16 and this movement is transmitted as an axial movement to the second shaft 14, that end of this shaft remote from the first sleeve sliding in the second sleeve 22; the arms 13 carrying the shaft 9 partake of this movement so that 5 the discs 11 have a simultaneous transverse adjustment.

The abutments with which the discs co-operate are in the form of circular flanges 27 on hubs 28, the flanges and hubs being bored to fit on a 10 third shaft 29 parallel with the shaft 9, the peripheral portions of the discs 11 being arranged to overlap the peripheral portions of the flanges 27 so as to effect a shear cut of a web passed over the flanges 27. The hubs 28 and flanges 27 are 15 a sliding fit on the third shaft 29 and are provided with grub screws 30 whereby they may be secured in a position corresponding to the position to which the corresponding discs are individually adjusted on the first shaft 9. This third 20 shaft is slidably and rotatably mounted at one end in a bearing 31 carried by the part 16 and the other end of this shaft 29 is rotatably mounted in a bearing 32 carried by and is prevented from moving axially with respect to a third sleeve 25 33 slidably mounted in the second part 23; into an extension 34 of the sleeve 33 extends a second 30 screwed member 35 having shoulders 36, 37 between which a flange 38 on a bearing cap 39 is received to prevent axial movement of the screwed member 35, this screwed member having an operating hand-wheel 40. Thus, by operating the 35 second screwed member 35 the third sleeve 33 can be slid and this movement is transmitted to the third shaft 29 as an axial movement so that 40 the abutments can be adjusted simultaneously to correspond with the simultaneous side lay adjustment of the discs. The third shaft 29 may, if desired, be supported between its ends by bearings 41 in which the shaft is slidably mounted. 45

It will be seen that by the manipulation of the handle 24 the extent to which the peripheries of the discs 11 overlap the peripheries of the flanges 27 forming the abutments can be regulated to 50 regulate the depth of cut. While the adjustment 45 to regulate the depth of cut by manipulation of the handle 24 is of necessity limited, due to the meshed gears 43 and 44, it is sufficient, when the material being cut by the discs is paper-thin, and may be made without seriously affecting the operation thereof. By provision of this structure, it is also possible to adjust the shafts 9 and 29 toward and away from each other, to compensate for smaller and larger diameter discs 11 and corresponding different diameter gears 44. 55

To provide for the rotation of the discs and abutments, the third shaft 29 is provided with a gear wheel 42 driven in any convenient manner. This third shaft 29 is provided with a second gear wheel 43 in mesh with a gear wheel 44 on the first shaft 9, so that rotation of the shaft 29 is transmitted to the shaft 9.

Apparatus constructed in accordance with the invention is of particular value in its application to printing machines in which the web (or webs) have a long path to follow before being severed into product lengths and folded, and especially when the machine is one of the kind known as intaglio printing presses, in which the web is required to pass around drying drums for effecting the drying of ink on the web: the long path and the drying drums (and also turner bars) are factors which tend to produce side lay wander of the web but by reason of the mechanism described, when once the slitters have been adjusted to produce the desired width of ribbon, they can be moved bodily to compensate for such wander.

What we claim is:—

- 25 1. Mechanism for cutting a web into ribbons and comprising a first shaft arranged to extend transversely with respect to a web to be cut, a plurality of cutting discs secured in adjustable spaced relationship to the shaft, a second shaft 30 parallel with the first shaft, a plurality of abutments secured in adjustable spaced relation to the second shaft, a third shaft parallel with the first and second shafts, means carrying one of the last mentioned shafts from the third shaft, means 35 for effecting axial movement of the other of the said last mentioned shafts, means for effecting axial movement of the third shaft, and means for effecting angular movement of the third shaft.
- 40 2. Mechanism for cutting a web into ribbons and comprising a first shaft arranged to extend transversely with respect to a web to be cut, a plurality of cutting discs secured in adjustable spaced relationship to the shaft, a second shaft parallel with the first shaft, a plurality of abutments 45 secured in adjustable spaced relation to the second shaft, a gear on the first shaft and a second gear on the second shaft and meshing with the gear on the first shaft, a third shaft parallel with the first and second shafts, means carrying one of the last mentioned shafts from the third shaft, means for effecting axial movement of the other of the said last mentioned shafts, a further gear on the said other shaft and adapted to be driven to transmit drive to 50 the said other shaft, means for effecting axial movement of the third shaft, and means for effecting angular movement of the third shaft.
- 55 3. Mechanism for cutting a web into ribbons and comprising a first shaft arranged to extend transversely with respect to a web to be cut, a plurality of cutting discs secured in adjustable spaced relationship to the shaft, a second shaft parallel with the first shaft, a plurality of abutments 60 secured in adjustable spaced relation to the second shaft, a third shaft parallel with the first and second shafts, means carrying one of the last mentioned shafts from the third shaft, screw and nut means for effecting axial movement of the other of the said last mentioned shafts, screw 65 and nut means for effecting axial movement of the third shaft, and means for effecting angular movement of the third shaft.

4. In a web cutting mechanism, a rotatable shaft having a plurality of abutments, each adjustably mounted thereon for axial adjustment relatively thereto, a rockable shaft, means to axially adjust said rockable shaft, a second rotatable shaft having a plurality of cutting discs thereon, each adjustably mounted thereon for axial adjustment relatively thereto, and means rockable with said rockable shaft to support said second rotatable shaft.

5. In a web cutting mechanism, a rotatable shaft having a plurality of abutments thereon, each adjustably mounted thereon for axial adjustment relatively thereto, said shaft being mounted for axial adjustment, a rockable shaft, 15 said rockable shaft being mounted for axial adjustment, a second rotatable shaft having a plurality of cutting discs thereon, each adjustably mounted thereon for axial adjustment relatively thereto, and means secured to said rockable shaft 20 and supporting said second rotatable shaft to connect the same, whereby said second rotatable shaft will move axially with, and be rocked by, said rockable shaft, and means to rock said rockable shaft.

6. In a web cutting mechanism, a first rotatable shaft having a plurality of spaced apart abutments thereon, a rockable shaft having shaft supporting arms thereon, a second rotatable shaft supported by said arms and having web cutting discs thereon spaced apart to cooperate with said abutments on said first shaft, means to axially adjust the rockable shaft, means to rock the rockable shaft, and means to lock the rockable shaft in any of its rocked positions.

7. In a web cutting mechanism, a first rotatable shaft having axially adjustable abutments thereon, a second rotatable shaft having abutment cooperating, axially adjustable cutting discs thereon, an axially adjustable member having 40 means to rotatably support one of said rotatable shafts, means to axially adjust the other of said rotatable shafts, and means to drive said rotatable shafts.

8. In a web cutting mechanism, a first rotatable shaft having axially adjustable abutments thereon, a second rotatable shaft having abutment cooperating, axially adjustable cutting discs thereon, an axially adjustable member having 45 means to rotatably support one of said rotatable shafts, means to rock said axially adjustable shaft supporting member to move the abutments and discs relatively to each other, means to lock said rockable member in any of its rocked positions, and means to drive said rotatable shafts.

9. In a web cutting mechanism, a first rotatable shaft having axially adjustable abutments thereon, a second rotatable shaft having abutment cooperating, axially adjustable cutting discs 60 thereon, an axially adjustable member having means to rotatably support one of said rotatable shafts, to simultaneously axially adjust all of the abutments and all of the discs relatively to each other, means to lock said axially adjustable shaft 65 supporting member in any of its axially adjusted positions, and means to drive said rotatable shafts.
